UNITED STATES PATENT OFFICE.

OLIVER T. HUNGERFORD, OF BELLEVILLE, NEW JERSEY.

BOMB.

1,372,141.

Specification of Letters Patent. Patented Mar. 22, 1921.

Application filed November 7, 1917. Serial No. 200,756.

To all whom it may concern:

Be it known that I, OLIVER T. HUNGERFORD, a citizen of the United States, residing at Belleville, Essex county, and State of New Jersey, have invented and discovered 5 certain new and useful Improvements in Bombs, of which the following is a specification.

My said invention relates to bombs, or 10 projectiles of the explosive type, and consists in the combinations and arrangements of elements hereinafter described and particularly set forth in the accompanying claims.

15 The invention has for its purpose to provide a bomb adapted for destroying or disabling submarines, deflecting torpedoes, and making warfare against such means of attack, and which may be fired from the air, 20 from guns, or from the shore, by hand or by any type of bomb thrower now in use.

A further purpose of the invention is to 25 produce a bomb, or projectile, adapted to be exploded by an electric current in a circuit arranged to be completed or closed by the action of the water as soon as the bomb is dropped therein; and having safety means for preventing premature explosion while 30 the bomb is being handled or through other cause.

The invention is disclosed by way of illustration in the accompanying drawing which shows a central vertical sectional view of the bomb.

35 Referring to the construction in further detail the bomb consists of a casing 1 preferably of spherical form having an open ended and cylindrical extension or neck 2, and constructed preferably of metal of suitable 40 thickness. The spherical portion 1 of the casing contains an explosive charge 3 having embedded therein the electrical means for igniting said charge when the bomb is submerged in water, and the cylindrical portion 2 contains the circuit closing means to 45 produce ignition of the primer and the safety device employed.

The ignition device consists of a battery 4 contained in a suitable receptacle 5, and 6 50 7 designate the conductor wires from the battery as shown. A resistance 8 is located in the conductor wires 7 and is utilized as one of the means for igniting the charge 3 to explode the bomb.

55 A coil 9 located in the casing 10, and connected to the battery, induces a current in

the secondary coil 11 that is connected with a detonator 12 and this constitutes a second means of exploding the charge. A wire 16, indicated by dotted lines, may connect 60 wires 6 and 7 between battery 4 and coil 9, which will shunt the current by said coil through resistance 8, heat said resistance and explode the charge. The shunt wire 16 is relied on to ignite the charge through the re- 65 sistance 8 in the event of failure of the coil. Otherwise the current that would pass through the wire 16 would be negligible.

The two wires 6 and 7 are led through a disk 13 and then through a suitable insulation 14 in the cylindrical part 2, and the ends of said wires are embedded in a removable safety cap 15 inserted in the end of the cylinder 2 to protect the ends of the wires until the bomb is to be used. A rib 17 is formed 70 between said wires to effectively guard the ends of the conductors against contacting with a tool used to remove the cap which would obviously operate to close the circuit and prematurely explode the bomb. It is 75 proposed to remove the plug or closure 15 just previously to throwing the bomb and any suitable form of instrument may be used for this purpose.

In operation an electric circuit is com- 85 plete as soon as the two ends of the conductors 6 and 7 are immersed in water, i. e., the water completes the electric circuit and causes the current to operate to heat the resistance, or the coil to operate the other 90 means, as explained, to ignite the charge and produce explosion thereof, through either of the means mentioned.

It is obvious that those skilled in the art may vary the details of construction and arrangement of parts without departing from the spirit of my invention, and therefore I do not wish to be limited to such features except as may be required by the 95 claims.

Having thus described my said invention what I claim as new and desire to secure by Letters Patent, is:

1. A projectile comprising a casing hav- 105 ing a neck, an explosive charge in the casing, ignition means disposed within the charge, insulating material filling the neck and forming a depression in the end, conductors passing through the insulating material to the ignition means and having terminals re- 110 posed within the depression and a closure for the depression wholly within the neck of

the casing and adapted to be manually removed and while in position to maintain the conductors in insulated condition.

2. A projectile comprising a casing, an explosive charge in the casing, ignition means communicating with the charge, a hollow handle communicating with the casing, conductors passing through the handle and connected with the ignition means, insulating material filling the handle and maintaining the conductors in spaced relation, the gap between the conductors adapted to be bridged by water, and manually removable, means to protect the conductors from water.

3. A projectile comprising a substantially spherical casing having a handle off-set radially from one side, an explosive charge with-

in the casing, insulating material filling the handle and forming a retainer for the explosive charge, an igniting circuit within the charge including a battery, terminals of this circuit extending outwardly through the insulating material and exposed within a hollow formed in such insulating material and a manually removable plug filling the hollow and maintaining the exposed terminals against contact.

In witness whereof, I have hereunto set my hand and seal at Washington, D. C., this ninth day of October, A. D. nineteen hundred and seventeen.

OLIVER T. HUNGERFORD. [L. S.]

Witness:

E. W. BRADFORD.
